Gerry P. Van Wye

UNITED STATES PATENT OFFICE.

CHARLES F. BERGER, OF PELHAM, NEW YORK.

CHALK-TROUGH.

1,352,720.

Specification of Letters Patent. Patented Sept. 14, 1920.

Application filed December 31, 1919. Serial No. 348,693.

To all whom it may concern:

Be it known that I, CHARLES F. BERGER, a citizen of the United States, residing at Pelham, in the county of Westchester and State of New York, have invented a new and useful Chalk-Trough, of which the following is a specification.

This invention relates to chalk troughs used with blackboards in school rooms; and the object of the invention is to provide a chalk trough in which the chalk dust will be deposited in a special receptacle from whence it can be removed easily without disturbing the chalk or erasers on the other part of the chalk trough. The special object of the invention is to provide a chalk trough provided with an open space for the insertion of the hand for cleaning the chalk dust. A further object of the invention is to provide joints of special construction that will not be separated, or get out of order in a manner to snare, or obstruct the hand.

The invention is illustrated in the accompanying drawings, in which—

Fig. 1, is a vertical section of a chalk trough constructed in accordance with my invention, applied to a blackboard;

Fig. 2, is a front elevation of a portion thereof; and,

Fig. 3, is a plan view of the same portion—a part of the blackboard and frame being in section.

In the drawing, like numerals of reference refer to the same parts in each of the views.

I have illustrated my improved chalk trough as made in sections; but it is evident that this is not necessary in all cases as the chalk trough could be constructed at the same time the frame for the blackboard is made.

As shown, I provide a bottom trough part 4, adapted to receive the chalk dust from the blackboard 5 in the usual manner. If the chalk trough is made up in sections, this part 4 may be made to extend out to the end of the blackboard frame, as shown in Figs. 2 and 3.

The upper part consists of a screen 6 on which the pieces of chalk, and erasers can be placed, while the chalk dust from the board will pass through to the part 4, where it will be caught by reason of the fact that the upper part of the part 4 is made in shape of a trough, as shown particularly in Fig. 1.

The screen of the upper part is supported

in the following special manner above the part 4 to leave the open space between the two parts for the insertion of the hand for cleaning. As shown, the screen 6 is mounted on a rail 8, supported by brackets 9, the inner ends of which are secured to the part 10, of the lower part 4, as clearly shown in Fig. 1. The outer end of each of the brackets is preferably rounded, and adapted to enter a socket 11 in the rail 8. The screen is preferably secured to the part 10 with nails, and to the rail 8 in the same way; but it is evident that the screen may be secured to these parts in any desired manner. Thus, when the brackets are in place the parts 8, 9, and 10 form a frame for the sure support of the screen 6, as will be clear. To completely conceal the rail 8, and brackets 9, the molding 12 is provided; which is preferably rounded in contour, and is provided with a recessed portion 13 adapted to receive the rail 8 with the screen attached, and extend to the bottom of the rail 8 so that the bottom of the rail 8 will be flush with the bottom of the molding and the bottom of the brackets will also be flush with the bottom of this molding. Thus there is nothing to extend from the upper part into the space 7 to interfere with the sweep of the hand in cleaning out the trough in the part 4.

I also prefer to provide the molding strip 14, which has a portion 15 extending over the screen and the part 10 so the chalk dust will have no lodging place, as will be understood, but will have to pass through the screen to the part 4.

Where the chalk trough is made up in sections for shipment I prefer to house the ends of the screen 6, with housings 16; so when the sections are placed together, there will be no possibility of the ends being bent downward to snag the hand of the person cleaning out the chalk dust in the part 4. This housing will also insure a perfectly smooth upper surface for the screen when the sections are placed together.

When made in sections, I may also provide the cleats 17, to connect the molding sections; and may provide the cleats 18 to connect the sections of the part 4.

I may also provide the end molding 19, so as to completely inclose the screen 6 that nothing may slide off the end of the screen. Where used, the strip 19 would not extend below the molding 12, so there would be

nothing to obstruct the hand in sliding along the space 7 in cleaning the trough in the part 4.

In operation, when it is desired to clean 5 the chalk dust from the trough in the part 4, a damp rag, or brush may be run along this trough for the purpose of cleaning out the dust. In this operation, the pieces of chalk and erasers, or other articles lying on the 10 screen 6 will not have to be removed, as will be clear. Thus a chalk trough is provided which can easily be cleaned without removing any portion of the trough from the blackboard; and in which there is nothing 15 to obstruct the hand of the cleaner.

By providing sections, these sections can be installed prior to the installation of the blackboard; and the sections can be secured together in the manner described. When 20 installed, the blackboard and chalk trough will form a substantial construction that will be pleasing in appearance and efficient in use.

As shown, the brackets are secured to the 25 part 10, of the lower part, which may be termed a riser with screws 20, passing through a screw hole in the bracket, as indicated with dotted lines; or the brackets may be secured to this riser in any desired 30 manner; but in any event it is desirable to recess the riser 10 for each bracket, as shown.

By the construction shown there is nothing 35 to catch the hand in passing the same along the trough in the lower part; and it will be understood that a brush, or damp rag can be passed along the trough for 40 cleaning purposes without having anything to catch the same, or having to remove any thing from the upper part.

I claim:

1. A chalk trough comprising two parts separated at the outer edge whereby a hand may be inserted between the parts, the lower 45 part being adapted to receive the chalk dust, and the upper part having a lower side free from obstructions.

2. In a chalk trough composed of two parts separated at the outer edge whereby a 50 hand may be inserted between them, a bracket adapted to be fixed in position and support the upper part, and a rail mounted on the outer ends of said brackets and lying flush with the under sides thereof.

55 3. In a chalk trough composed of two parts separated at the outer edge whereby a hand may be inserted between them, brackets fixed in position and supporting the outer edge of the upper part, a rail mounted

on the outer ends of said brackets and lying 60 flush with the lower sides thereof, and a molding strip adapted to embrace said rail and lie coterminous with the bottom thereof.

4. In a chalk trough composed of two parts separated at the outer edge whereby 65 a hand may be inserted between them, brackets fixed in position and supporting the outer edge of the upper part, a rail mounted on the outer ends of said brackets and lying flush with the lower sides thereof, a screen 70 mounted on said brackets and rail, and a molding strip adapted to embrace the outer edge of said screen and the rail and lie coterminous with the bottom of the rail.

5. In a chalk trough composed of two 75 parts separated at the outer edge whereby a hand may be inserted between them, brackets fixed in position and supporting the outer edge of the upper part, a rail mounted on the outer ends of said brackets and lying 80 flush with the lower sides thereof, and a screen mounted on said brackets and rail.

6. A chalk trough composed of sections, each section comprising two parts separated at the outer edge for the insertion of the 85 hand, the lower part having a trough-shaped projecting portion adapted to receive the chalk dust and a riser, a plurality of brackets let into, and secured to said 90 riser, a rail having a mortise and tenon connection with said brackets in a manner whereby the lower side of the rail is flush with the under sides of the bracket, a screen mounted on said riser, brackets, and rail, and having protected ends, and a molding 95 strip embracing said rail and the outer edge of said screen in a manner to lie flush with the bottom of said rail.

7. A chalk trough comprising two parts separated at the outer edge for the insertion 100 of the hand, the lower part having a trough-shaped projecting portion adapted to receive the chalk dust and a riser, a plurality of brackets let into, and secured to said riser, a rail having a mortise and tenon connection 105 with said brackets in a manner whereby the lower side of the rail is flush with the under side of the brackets, a screen mounted on said riser, brackets, and rail, and having protected ends, a molding adapted to direct 110 the chalk dust through said screen into said trough-shaped part, and a molding strip embracing said rail and the outer edge of said screen in a manner to lie flush with the bottom of said rail.

Dated 29th day of December, 1919.

CHARLES F. BERGER.
